ELECTRIC TUMBLER SWITCH

Robert H. Bentley, Hartford, Conn., assignor to
 The Arrow-Hart & Hegeman Electric Company, Hartford, Conn., a corporation of Connecticut

Application February 7, 1936, Serial No. 62,845

5 Claims. (CL 200—16)

This invention relates to electric snap switches. More particularly it relates to electric snap switches of the tumbler type and has for an object the provision of means to extinguish or 5 quench an arc which may develop between the fixed and movable contacts during the contact separating movement.

Another object of this invention is to provide a tumbler electric snap switch with means to 10 positively insulate the current carrying contacts from each other when the switch is in open circuit position.

A further object of this invention is to provide common means for supporting the snap mechanism and for shielding the snap mechanism 15 from the live parts of the switch.

Other objects and advantages of my invention will become apparent as it is described in connection with the accompanying drawing:—

20 In the drawing

Figure 1 is a plan view looking into the interior of a switch constructed according to the principles of my invention, when the contact actuating mechanism has been removed.

25 Figure 2 is a longitudinal vertical section view of the tumbler snap switch shown in Figure 1 with the section taken along line 2—2 of Figure 1, when the switch is fully assembled.

Figure 3 is a longitudinal vertical section taken 30 along line 3—3 of Figure 1 of my switch, as shown in Figure 1.

Figure 4 is a longitudinal vertical section view like Figure 3, but with the parts in open circuit position.

35 Figure 5 is a perspective view of the contact operating yoke and bar.

Referring to the drawing the switch parts are mounted within a rectangular insulating casing having a bottom formed integrally with the side 40 walls of the casing and having an open top. The casing is partially hollowed out and recessed at appropriate points for the reception of the switch parts, as will be more fully described. Adjacent each corner, the switch casing is hollowed out to form rectangular recesses 10r. Of these recesses, those on the same side of the casing are joined by a narrow vertical slot or 45 passage 58 in which contact carrying insulating plates 44 and 46 slide as will be hereinafter more particularly described. In opposite walls of these recesses 10r adjacent the end walls 10e of the casing there are provided grooves for the accommodation of the edges of wire terminals 12, 14, 16 and 18 which may be formed of rectangular 50 sheet metal stampings having threaded apertures

in one end for the accommodation of terminal screws 20. The end walls of the casing are cut through adjacent each bottom corner and providing access to the wire terminals from the exterior of the casing and for the accommodation of the wire terminal screws 20. Riveted to the top portions of the wire terminals 12 and 14 are L-shaped resilient strips of sheet metal 22 and 24 forming stationary contacts of which the longer leg extends along the side of the casing 10 adjacent the top edge. The shorter legs of these contact members are secured by rivets 26 to their respective wire terminals. The side walls of the casing are recessed or stepped back to provide a passage for the longer legs of these 15 contact members.

Secured to the top portions of the wire terminals 16 and 18 by rivets 28 are the shorter legs of L-shaped strips of sheet metal forming additional stationary contact members 36 and 38, 20 the longer legs of which extend, adjacent the center line but on opposite sides of a rectangular barrier or post 10p remaining within the interior of the switch casing. The extremities of the contact members 22, 24, 36 and 38, all lie within the 25 central zone of the switch casing and may, but need not, necessarily be in overlapping relation. In the preferred embodiment of the invention illustrated, the ends of these contact members are adapted to be engaged by movable bridging 30 contacts 40 and 42 formed from strips of sheet metal bent into U-shape and then having their ends bent in opposite directions parallel to the base of the U. These bridging contact members are each carried by a piece of rectilinearly movable sheet insulation 44 and 46 respectively. These contact carrying insulating plates are adapted to slide longitudinally back and forth within the casing in longitudinally extending passages at 50, the sides of which form guiding surfaces to ensure rectilinear movement of the plates. The bottom edges of the plates are adapted to slide upon the bottom of the casing. The plates may be substantially rectangular in shape with their lower corners cut away so as not to 45 engage with the shanks of the terminal screws 20 which extend within the casing in the neighborhood of the path of movement of these insulating plates, as may be seen best by referring to Figures 3 and 4.

In order to support the bridging contacts 40 and 42, the insulating plates 44 and 46 are each provided with a pair of short parallel slots extending perpendicularly in from the central portion of the top edges of the plates. The bridging 55

contacts are slid edgewise into these slots with the central parts of the contacts lying against the inside surfaces of the plates and the ends of the contacts lying against the outsides of the 5 plates. The depth of these slots is determined by the position which the bridging contact must occupy in order to engage with its stationary contacts. In the embodiment shown, the upper edge of the bridging contact is flush with the 10 upper edge of the contact carrying insulating plate.

In order to move the insulating plates and to cause engagement and disengagement of the bridging contacts with their cooperating stationary contacts, a recess or slot such as 46s is 15 cut in the central portion of the bottom edge of each of the plates into which recesses the ends of an actuating rod or pin 60 extend. This pin is carried by a U-shaped sheet metal stamping 20 or yoke 62, the pin extending through the legs 62a of the yoke adjacent the bridging portion 62b thereof. This yoke is capable of oscillation under the action of a snapping mechanism hereinafter more particularly described. The yoke 25 is supported by having the ends of its legs outward turned in opposite directions and bent into semi-circular form as at 62c and supported in semi-circular bearing recesses 63 in the top edges of insulating inserts 66 and 68.

30 These insulating inserts 66 and 68 are stamped from sheet insulation in the irregular form illustrated in Figure 2 and are adapted to stand vertically in the switch casing with their ends received in vertical slots 10, 12, 14 and 16, which 35 are formed in the casing beside the posts 10p and parallel to the slots 50. The inserts 66 and 68 have openings such as 68a formed in their bottom edges to permit free swinging movement of the actuating rod or pin 60 as will hereinafter 40 more fully appear.

On the top of the insulating casing there is a 45 rectangular sheet insulation cover 80 having a central aperture therethrough for the inner end of a conventional switch operating lever 82 which may be mounted in the neck of a threaded nipple 84 which in turn is mounted in a metallic top 50 plate 86 in a conventional fashion. This metallic plate may be secured to the insulating casing by bolts 88 which pass through the casing from back to front and take into threaded apertures in the plate. Any suitable form of snap mechanism 55 may be applied between the end of the switch operating lever and the actuating yoke 62. Since the snapping mechanism forms in itself no part of this invention I have omitted showing it in detail in the interest of clearness. A snap mechanism which I have found to be particularly adapted for use in my switch is described and illustrated in the patent to Monroe Guett No. 60 1,335,106, patented March 30, 1920.

From the foregoing it will be apparent that as the switch operating lever is moved from right to left the actuating yoke 62 is caused to swing about its pivot bearings to the right from the position shown in Figure 2, and in so doing the ends of the rod 60 being engaged with the sides of the slots in the contact carrying plates, for instance with 46s, will cause the contact carrying plates 44, 46 to move from the position shown in 65 Figure 4 to that shown in Figure 3 thereby bringing the bridging contact into engagement with the stationary contacts and completing the circuit between wire terminals 16 and 12, and 18 and 14. Upon reverse movement of the operating 70 handle, the contact carrying plates 44 and 46

will move in the opposite direction, that is from the position shown in Figures 1 and 3 to the position shown in Figure 4 thereby breaking the circuit and bringing the upper edge of the contact carrying plates between the stationary contacts and effectively insulating the stationary contacts as well as quenching or extinguishing any arc which may have developed upon the contact separation. It should be observed that the insulating inserts 66 and 68 not only support the 10 actuating yoke 62 but also insulate it and the snap mechanism from the contacts thereby prohibiting the possibility of an arc playing into the snap mechanism and at the same time removing the likelihood of engagement of any metal part or 15 object with the snap mechanism and with the live parts of the switch whereby a person operating the switch might receive a shock.

Many modifications within the scope of my invention will occur to those skilled in the art, 20 therefore I do not limit the invention to the specific embodiment shown.

I claim:—

1. In a tumbler snap switch, an insulating casing, fixed contacts mounted at opposite ends and 25 extending toward the center of the casing, an insulating plate parallel to the side wall of said casing and movable between said contacts and forming a baffle between them in open circuit position of the switch, a bridging contact mounted 30 on said plate and adapted to bridge said fixed contacts, snap mechanism for moving said plate, insulating plates inserted in slots in said casing on opposite sides of said snap mechanism and shielding said fixed contacts from said snap 35 mechanism, said inserted plates supporting said snap mechanism.

2. In a tumbler switch, an insulating casing, 40 fixed contacts mounted in said casing and having oppositely directed faces, a bridging contact slideable between said faces, mechanism for moving said bridging contact with a snap, a pair of insulating plates on opposite sides of said snap mechanism affording support for said snap mechanism and shielding it from said fixed contacts, 45 said supporting plates being inserted in slots in said casing from the front of the casing.

3. In a tumbler switch, an insulating casing, pairs of fixed contacts at opposite sides of the 50 casing, the contact faces of each pair facing oppositely, a pair of rectilinearly movable insulating plates movable between said pairs of fixed contacts, a pair of bridging contacts for connecting said pairs of fixed contacts and mounted on said plates, snap mechanism between said pairs of 55 fixed contacts, insulating plates between said snap mechanism and said fixed contacts and supporting said snap mechanism, a swinging rod carried by said snap mechanism and engaging with said contact carrying plates to cause movement 60 of said contact carrying plates as said snap mechanism is actuated.

4. In a tumbler switch, an insulating casing, 65 pairs of fixed contacts on opposite sides of said casing, bridging contacts for connecting the fixed contacts of the respective pairs, insulated supporting means for said bridging contacts, snap mechanism including a swinging rod engaging with said bridging contact supporting means for 70 moving said bridging contacts as said mechanism is actuated, and insulating supporting means for said snap mechanism insertable into said casing from the front and shielding said snap mechanism from said fixed contacts.

5. In a tumbler switch, an insulating casing, pairs of fixed contacts on opposite sides of said casing, bridging contacts for connecting the contacts of the respective pairs, insulated supporting means for said bridging contacts, snap mechanism including a swinging rod engaging with said bridging contact supporting means for moving

said bridging contacts as said mechanism is actuated, and a pair of insulating plates having their ends fitted into slots in said casing supporting said snap mechanism and shielding it from said fixed contacts.

5

ROBERT H. BENTLEY.
